(57) **CLAIM**

The ornamental design for a resuscitation bag, as shown and described.

DESCRIPTION

FIG. 1 is a perspective view of a resuscitation bag showing our new design made of a translucent material;

FIG. 2 is a front elevation view thereof;

FIG. 3 is a rear elevation view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view thereof taken along line 8-8 of FIG. 6;

FIG. 9 is a perspective view of a second embodiment of our claimed design;

FIG. 10 is a front elevation view thereof;

FIG. 11 is a rear elevation view thereof;

FIG. 12 is a right side elevational view thereof;

FIG. 13 is a left side elevational view thereof;

FIG. 14 is a cross-sectional view thereof taken along the line 14-14 of FIG. 15;

FIG. 15 is a top plan view thereof;

FIG. 16 is a bottom plan view thereof;

FIG. 17 is a perspective view of a third embodiment of our claimed design;

FIG. 18 is a front elevation view thereof;

FIG. 19 is a rear elevation view thereof;

FIG. 20 is a right side elevational view thereof;

FIG. 21 is a left side elevational view thereof;

FIG. 22 is a top plan view thereof;

FIG. 23 is a bottom plan view thereof;

FIG. 24 is a perspective view of a fourth embodiment of our claimed design;

FIG. 25 is a front elevation view thereof;

FIG. 26 is a rear elevation view thereof;

FIG. 27 is a right side elevational view thereof;

FIG. 28 is a left side elevational view thereof;

FIG. 29 is a top plan view thereof; and,

FIG. 30 is a bottom plan view thereof.

(Continued)

The broken lines shown in the drawings are included for the purpose of illustrating portions of the article and form no part of the claimed design.
